LADY'S BELT

Catherine C. Wade, St. Louis, and Jaquelin C. Sherman, St. Louis County, Mo.

Application November 5, 1948, Serial No. 149,474

Term of patent 3½ years

(Cl. D3—10)

To all whom it may concern:

Be it known that we, Catherine C. Wade and Jaquelin C. Sherman, citizens of the United States, residing at St. Louis and St. Louis County, respectively, Missouri, have invented a new, original, and ornamental Design for a Lady's Belt, of which the following is a specification, reference being had to the accompanying drawing, forming part hereof.

We claim:

The ornamental design for a lady's belt, substantially as shown.

CATHERINE C. WADE.
JAQUELIN C. SHERMAN.
